D. R. COLLIER.

CHAIR IRON.

APPLICATION FILED MAR. 17, 1921.

1,399,466.

Patented Dec. 6, 1921.

UNITED STATES PATENT OFFICE.

DAVID R. COLLIER, OF GARDNER, MASSACHUSETTS, ASSIGNOR TO COLLIER-KEYWORTH COMPANY, OF GARDNER, MASSACHUSETTS, A CORPORATION OF MASSACHUSETTS.

CHAIR-IRON.

1,399,466.

Specification of Letters Patent.

Patented Dec. 6, 1921.

Application filed March 17, 1921. Serial No. 452,898.

To all whom it may concern:

Be it known that I, DAVID R. COLLIER, a citizen of the United States, residing at Gardner, in the county of Worcester and 5 State of Massachusetts, have invented new and useful Improvements in Chair-Irons, of which the following is a specification.

This invention has relation to chair irons of the general type of those illustrated in 10 my application, Serial No. 429,341, filed on the 9th day of December, 1920, in which the hub comprises a central tubular member and a plurality of channel bars grouped therearound to receive the inner ends of 15 the legs.

The present invention comprises certain improvements, both in hub construction and in the means for detachably connecting to the hub the plate or member which supports 20 the adjusting screw shown in said application.

On the accompanying drawing,—

Figure 1 represents a perspective view of a hub embodying my invention.

Fig. 2 represents a plan view of a hub with the screw-supporting member or plate in place, the spindle being shown in section.

Fig. 3 represents a vertical section through the hub, and portions of the legs, on the line 30 3—3 of Fig. 2.

Fig. 4 represents a section on the line 4—4 of Fig. 3.

Fig. 5 represents a similar section with the parts in position to permit the detachment 35 of the screw-supporting plate.

Fig. 6 represents a section on the line 6—6 of Fig. 3.

The hub comprises a central tube 10, and a plurality of channel bars 11 equally spaced about said tube as shown in Fig. 1. Each channel bar has the longitudinal upright forwardly-converging webs 12, which webs also converge upwardly, so that the inner ends of the legs 13 may be driven 40 or wedged therein. The upper ends of the webs 12 on channel bars have lugs or studs 14 projecting therefrom, and the body portions of the channel bars have at the lower ends the depending lugs 15. Encircling the 45 upper end of the central tube 10, there is an upper plate 16, which may have a dependent flanged rim 17, said plate being held on said tube between a circumferential bead 18 thereon and the peened or outwardly spun end 19. The plate has a plurality of aper-

tures to receive the studs 14, the ends of which are upset. Thus the upper end of the tube, the webs 12 of the channel bars and said plate are all secured rigidly together. The lower end of the tube and the channel 60 bars are secured together by a tapering collar 20 having an inturned flange 21. The collar is forced upon the end of said tube and on the lugs 15, and wedges or crowds the lower ends of the channel bars toward and 65 against the central tube, the lower end of which projects a short distance below or beyond said lugs. Thus the lugs and the collar have a wedging relation. The end of the tube is peened or spun outwardly as at 70 22 to overlap the collar and hold it rigidly in place. After the chair legs are introduced into the channel irons, a bottom plate 23, having radiating arms 24 and a central aperture 25 just adequate to receive the collar 20, is slipped on the collar, and is secured to the legs by wood screws 26 passed through holes in said radiating arms. The 75 legs are likewise secured to the top plate 16 by screws 27.

The means, by which the spindle 28 supports the head (not shown) is not illustrated, except the dished plate 29 which has an aperture 30 to afford a step bearing for an adjusting screw (not shown), such as 80 illustrated and described in my application hereinbefore mentioned. Said plate 29 is fixed rigidly upon a short sleeve 31, on which there is also a collar 32 and a locking disk or member 33. The plate, the collar 85 and the disk are all rigidly held upon the sleeve between the bead 34 thereon and the outwardly-spun or peened end of said sleeve. The disk 33 serves as one of two interlocking members by which the plate is locked to the 90 hub, the other interlocking member being indicated at 35. Said last-mentioned member consists of a curved strip having at its upper edge an inturned flange 36 to take over the edge of the disk 33, and having lugs 100 or ears 37 through which rivets 38 are passed into the top plate 16 of the hub. The disk 33 is recessed or notched at 39, so that, when the two members 35 and 33 occupy the relative positions shown in Fig. 5, the spindle 28 and the adjustment screw-supporting plate 29 may be lifted bodily in disengagement from the hub, or may be placed on the hub. When the notch 39 is out of registration with the flange or lip, as in Fig. 4 for 105 110

instance, the plate and the hub are interlocked.

What I claim is:—

1. A chair iron hub comprising a central tubular member, a plurality of channel irons disposed about said member and having projecting lugs at one end, and a collar on said tubular member engaging said lugs and securing them to said member.

10 2. A chair iron hub comprising a central tubular member, a plurality of channel irons disposed about said member and having projecting lugs at one end, and a collar on said tubular member engaging said lugs and securing them to said member, said lugs and said collar being formed to provide a wedging action to force said channel irons toward said tubular member.

20 3. A chair iron hub comprising a central tubular member, a plurality of channel irons disposed about said member and having projecting lugs at one end, a collar on said tubular member engaging said lugs and securing them to said member, and a leg-securing

plate encircling said collar and removable 25 therefrom.

4. A chair iron hub comprising a central tubular member, a plurality of channel irons disposed about said member and having projecting lugs at one end, and a collar on said tubular member engaging said lugs and securing them to said member, said collar being tapering and having an inturned flange 30 at its smaller end.

5. A chair iron comprising a hub having 35 a top plate, a spindle journaled in said hub and slideable axially therein, a plate rotatable about the axis of said spindle and resting on said hub, a notched disk secured to said plate, and a member on said hub adapted to register with the notch in said disk and to overlap the unnotched portion of said disk and thereby lock said plate and said hub together 40 without interfering with their relative rotative movement.

In testimony whereof I have affixed my signature.

DAVID R. COLLIER.
